UNITED STATES PATENT OFFICE.

PERCIVAL JOHN PURDY, OF LONDON, ENGLAND.

BOTTLE-LABELING MACHINE.

Application filed June 13, 1923 Serial No. 645,130.

To all whom it may concern:

Be it known that I, PERCIVAL JOHN PURDY, a subject of the King of Great Britain, residing in London, England, have 5 invented certain new and useful Improvements in Bottle-Labeling Machines, of which the following is a specification.

This invention relates to bottle labeling machines and it refers to machines of the 10 type in which the labels are placed in a label magazine from which they are removed by pickers having surfaces to which gum is applied, the pickers carrying the label to a position ready for application to 15 the bottle, said label being held upon the bottle by a grip finger the final application of the label being effected by means of wipers having rubber flaps or the like engaging the label and pressing it down on to 20 the bottle.

The present invention has for its object 25 to provide simple and efficient means adapted to be applied to an existing machine whereby the date of labeling or other particulars or information may be printed upon the back of the label prior to its removal from the magazine.

In order that the invention may be the 30 better understood drawings are appended in which:—

Fig. 1 is a side view showing part of a machine embodying the present invention,

Fig. 2 is a view seen from the opposite side of the machine,

Fig. 3 is a front view of certain parts,

Fig. 4 is a view showing more clearly the arrangement of the inking rollers.

In the accompanying drawings, in which only such parts of the main machine are 40 shown as are necessary to the proper understanding of the invention, 1 indicates a plate or bracket having lugs 2 at each end bored to permit the passage of the rods 3, supporting the label magazine, indicated generally by 4. The rods 3 are carried by the arm 5 of the machine.

6 indicates a fly nut whereby the plate 1 is adjustably secured in position on rods 3.

Disposed upon the outer face of plate 1 50 are bearings supporting a spindle 8 upon which is secured a toothed wheel 9 engaging a rack 10 supported upon its underside by a channelled guide 11 secured to plate 1, the plate 1 being suitably slotted to accommodate the toothed wheel 9. The rack at its outer 55 end is bent or inclined upwards as shown

whereby, as will be presently more fully explained, as the rack moves inward the inner end is raised to bring the type into contact with the labels, indicated by *x*.

The rack at its inner end is provided with a type-holder 12 containing type preferably in intaglio.

Encircling the spindle 8 is a helical spring 13 secured at one end to said spindle and 65 at the other attached to one of the bearings for said spindle the action of said spring being to oppose the inward movement of the rack 10. Secured to one end of spindle 8 which is suitably extended for the purpose 70 is a pulley 14 attached to which is one end of a chain 15 passing over a guide pulley 16 and connected at its other end to one of the arms 17 carrying the roller 18 by which 75 gum is applied to the label pickers indicated by 19. The chain is connected to the arm 17 in any suitable manner preferably by means of the plate 20 secured to said arm and provided with a series of holes 21 whereby the point of attachment of the chain to the arm may be varied to alter the 80 effective length of the chain to secure the desired rotation of spindle 8.

22 indicates an arm secured to plate 1 and projecting rearwardly thereof being bored at its outer end for the passage of a rod 23 in carrying at its lower end a frame 24^a in which are secured rollers 25^a, 26, 27 the spindles of which are free to move vertically 90 in the slots 28 formed in the side members 90 of the frame 24^a.

The roller 25^a is formed of solid metal the weight acting to keep rollers 26, 27, which are provided with an absorbent outer covering in contact one with the other at 95 the same time allowing them to rise as they encounter the type. The ink may be applied to the rollers 26, 27 from time to time as required by hand, or any other suitable provision may be made whereby the ink is automatically applied to said roller.

In order to obtain a continuous rotation of the ink rollers whereby the more even wear is secured and even distribution of the ink, there is pivotally mounted at 22^a upon 105 the side of the arm 22 a bell crank lever 23^a the bent end of which engages a slot in the rod 23 which is freely slidable in the arm 22. The latter is frictionally held by means of a spring washer or other device and at 110 its lower end it projects into the path of screws 24, 25 which screws engaging the

lever according to the direction of motion of the rack 10 cause said lever to tilt to bring the inking rollers into or out of position to engage the type. By this means a continuous rotary motion is imparted to the inking rollers which rotate only as the type move into position beneath the labels.

The action of the parts is as follows:—

- 10 As the arms 17 move outwards to bring the roller 18 out of contact with the roller w in the gum reservoir w^1 the chain 15 is tightened and overcoming the spring 13 acts upon the spindle 8 causing same to rotate and the pinion 9 moves the rack 10 inwards 15 in a straight line until meeting the bent end of the said rack when the same is tilted causing the type at the inner end of the rack to impress the undersurface of the lowermost label x .
- 20 During the forward motion of the rack the ink rollers have been in their lowered position and contact with the type. As the rack approaches its innermost position the screw 24 contacting with the end of lever 25 tilts same lifting the inking rollers clear 30 of the type where they remain until the type are again drawn backward when the screw 25 engaging the opposite side of the lever again tilts it to lower the said inking rollers. On the return movement of the arms 17 the chain 15 is slackened permitting 35 spring 13 to rotate the spindle 8 and return the parts to their normal position.

Claims.

- 35 1. In a bottle labeling machine in combination, a label magazine, a body disposed beneath and clear of the labels in said magazine, a rack upon said body one end of said rack being upwardly inclined, a pinion engaging said rack, a shaft supporting said pinion, a spring opposing the movement of said pinion in one direction, means for operating the pinion against the action of the spring, type upon said body and means for inking said type.
- 40 2. In a bottle labeling machine in combination, a label magazine, a body disposed beneath and clear of the labels in said magazine type upon one end of said body, a rack 45 upon said body one end of said rack being upwardly inclined, a pinion engaging said

rack, a shaft supporting said pinion, a spring opposing the movement of said shaft in one direction, a pulley on said shaft, a flexible body having one end connected to 55 said pulley and the other to a reciprocating member of the machine and means for inking the type.

3. In a bottle labeling machine in combination, a label magazine, a body disposed beneath and clear of the labels in said magazine type upon said body, a rack upon said body, one end of said rack being upwardly inclined a pinion engaging said rack, a shaft supporting said pinion, a spring opposing 60 the movement of said shaft in one direction, a pulley on said shaft, a flexible body having one end connected to said pulley and the other to a reciprocating member of the machine, and means for inking the type comprising 65 a rod, a frame upon said rod, means for supporting said rod and rollers having their spindles freely movable in said frame to permit them to move longitudinally thereof.

4. In a bottle labeling machine in combination, a label magazine, a body disposed beneath and clear of the labels in said magazine type upon said body, a rack upon said body one end of said rack being upwardly 80 inclined, a pinion engaging said rack, a shaft supporting said pinion, a spring opposing the movement of said shaft in one direction, means for inking the type comprising a rod, means for slidably supporting said rod, a frame upon said rod, rollers having their spindles freely movable in said frame to prevent their movement longitudinally thereof, a bell crank lever, a slot in the rod engaged by one end of the lever, projections upon the reciprocating type carrying body engaging the other end of said lever whereby it is operated to cause the inking roller to be brought into a position to ink the type or held clear of said type.

In testimony whereof I have hereunto set my hand and affixed my seal in the presence of two witnesses.

PERCIVAL JOHN PURDY.
